SWITCH EQUIPPED TUBULAR CONSTRUCTION

Filed June 1, 1936

UNITED STATES PATENT OFFICE

2,065,403

SWITCH EQUIPPED TUBULAR CONSTRUCTION

Frank W. Schwinn, Chicago, Ill.

Application June 1, 1936, Serial No. 82,969

1 Claim. (Cl. 200—157)

My invention relates more particularly, though not exclusively, to the equipping of the tubular handle-bars of cycles with switch devices for controlling electrically controlled, or operated, devices thereon such, as for example horns, or lamps, particularly those which it is desired to be flashed on or off by the rider.

My objects are to provide for the equipping of tubular members with switch devices at relatively low cost; to afford a neat and trim appearance to the switch and tubular member assembly; to render the tubular member free of objectionable projecting parts; and other objects as will be manifest from the following description.

15 Referring to the accompanying drawing:

Figure 1 is a plan view of a handle-bar of a cycle equipped with a switch device in accordance with my invention.

Figure 2 is a broken section taken at the line 20 2 on Fig. 1 and viewed in the direction of the arrow.

Figure 3 is a plan view of the construction of Fig. 2 showing the handle-bar in section; and

25 Figure 4, a section taken at the line 4 on Fig. 2 and viewed in the direction of the arrow.

Referring to the particular illustrated preferred embodiment of my invention shown as applied to a handle-bar of a cycle represented at 5 and formed of tubing; it comprises electric switch mechanism involving a switch assembly comprising a block 6 of current insulating material, shown as of general cylindrical form with diametrically opposed recesses 7 therein at one end, and of a size to be introduced into the open end 30 of the handle-bar to the desired position therein; in the particular construction shown into position in one of the rearwardly extending hand-grip-forming ends 8 of the handle-bar commonly provided with hand grips 9.

40 The block 6, preferably formed as a one-piece structure, forms a support for two electric contact strips 10 and 11 extending lengthwise of the block beyond one end on the latter, these contacts being located in one of the recesses 7 and secured to the block by a screw bolt 12. The contacts 10 and 11 are relatively movable, in the construction shown being normally out of contact with each other. Preferably both contact strips are of spring metal, contact between them 45 being made by pressing the free end of the con-

tact 10 into engagement with the free end of the contact 11.

5 Wires 13 and 14 leading from any suitable source of electric current supply and in one of which the electrical device, as for example a horn (not shown) to be controlled or operated by the switch, is interposed, are in electrical contact, respectively, with the contact 11 and the contact 10, through the screw bolt 12, a strip of insulation 15 interposed between these contacts at the block 10 5 insulating these contacts from each other.

The switch also comprises a push button 16 preferably of current insulating material, located, and reciprocable in, an opening 17 in the upper portion of the side wall of the handle-bar at a point convenient for operation by the thumb of the rider of the cycle while grasping the adjacent hand grip 9, the button 16 and contact 10 having interengaging parts whereby an operative connection is provided between 20 these members for operating the contact 10 by the push button. Preferably the connection between the push button and the contact 10 is provided by forming the push button with an annular groove at its inner end as represented at 25 18 and slotting the free end of the contact 10 as represented at 19 thus causing it to present a yoke portion the arms 20 of which in the assembled position of the parts extend into the groove 18 in the button. 30

In the particular construction shown the groove 18 is provided by screwing part way into the body of the button 16, a screw represented at 21 the head of which is spaced from the underside of this body portion. 35

In this particular construction the assembled block 6, contacts 10 and 11, and the wires 13 and 14 connected therewith, and with the push button 16 inserted into the opening 17 in the bar, are inserted, as a unit into the open end 40 of the handle bar and pushed therein into a position in which the yoke arms 20 enter the groove 18 in the push button; and the block 6 then secured in place in the bar as for example by pinning it to the bar as represented at 22. 45

Inasmuch as the switch parts are housed within the handle bar, the only part exposed being the push button 16, the bar is caused to be free of any objectionable projecting parts and presents an exceedingly trim and neat appearance. 50

While I have illustrated and described a particular embodiment of my invention I do not wish to be understood as intending to limit it thereto as the same may be variously modified and altered and the invention embodied in other forms of structure without departing from the spirit thereof.

What I claim as new and desire to secure by Letters Patent, is:

- 5 10 In combination with a tubular member having an opening in the side wall thereof, an electric switch having a push button with a groove in its

side surface and insertable to position through said opening, said switch comprising a support and relatively movable contacts thereon insulated from each other and insertable into place in said member through an end of the latter, 5 one of said contacts having a portion which becomes positioned in said groove in the positioning of said switch parts in said member following the positioning of said push button in said opening, for the purpose set forth. 10

FRANK W. SCHWINN.
